UNITED STATES PATENT OFFICE.

TOM E. ROOKE, OF CEDAR RAPIDS, IOWA, ASSIGNOR TO THE JOHNSON GAS APPLIANCE COMPANY, OF CEDAR RAPIDS, IOWA.

TINSMITH'S FURNACE.

Application filed September 13, 1920. Serial No. 410,032.

To all whom it may concern:

Be it known that I, Tom E. Rooke, a citizen of the United States, and resident of Cedar Rapids, in the county of Linn and 5 State of Iowa, have invented a certain new and useful Tinsmith's Furnace, of which the following is a specification.

This invention relates to that class of furnaces designed to heat tinner's coppers and 10 other articles, by heat from a Bunsen gas burner.

The object of my invention is to provide means of simple, durable and inexpensive construction, whereby the supply of gas to 15 the furnace is automatically turned on by the act of placing a soldering copper in position on the furnace, and automatically cut off upon the removal of same, whereby a great economy in the use of gas is effected 20 and the convenience of the operator is promoted.

My invention consists in the construction, arrangement and combination of the various parts of the device, whereby the objects contemplated are attained, as hereinafter more 25 fully set forth, pointed out in my claims, and illustrated in the accompanying drawings, in which:

Figure 1 shows a side elevation of a furnace embodying my invention. The dotted lines to the right of said figure show the 30 gas controlling mechanism in position for shutting off the gas when the soldering copper has been removed.

Figure 2 shows a detail, vertical, central, 35 sectional view, taken on the line 2-2 of Figure 3, illustrating the automatic gas controlling device; and

Figure 3 is a detail end view, illustrating 40 the automatic gas controlling device.

Referring to the accompanying drawings, I have used the reference numeral 10 to indicate the base of the furnace, and 11 a hinged cover. The base and the hinged 45 cover are designed to receive between them a soldering copper 12. A gas supply pipe 13 is suitably supported in the base, and is designed to supply gas to the cylindrical body portion 14 of the mixer of the Bunsen burner. 50 The gas passage enters this cylindrical chamber at about its central portion, as clearly shown in Figure 2, and at the other end of the cylindrical portion is a gas discharge nipple 15, which enters the mixing

chamber 16, and the mixing chamber dis- 55 charges into the furnace.

Slidably mounted in the cylindrical chamber 14 is a gas controlling plug 17, arranged for free longitudinal movement, and when in the position shown in Figure 2 it cuts off 60 the supply of gas from the pipe 13, but when withdrawn, as shown by solid lines in Figure 1, it permits gas to pass from the pipe 13 into the nipple 15.

For automatically controlling the movement of the gas controlling plug 17, I have provided a lever 18 hinged to the base between the lugs 19 and provided at its lower end with a slot 20 through which a set screw 21 is passed, and said set screw is seated in 70 the gas controlling plug 17.

By this arrangement it is obvious that the amount of gas admitted to the furnace when the burner is open may be readily, easily and quickly adjusted by manipulation of 75 said set screw 21. If, for instance, the gas pressure is unusually high the set screw is moved to position so that when a copper is placed on the rest 23 the plug 17 will only partially uncover the gas supply pipe and 80 when the pressure of gas is relatively low the set screw 21 may be screwed into the plug further so that when the plug is in its open position it will entirely uncover the gas supply pipe. 85

An extensible coil spring 22 is interposed between the upper end of the lever 18 and the base 10, to normally hold the gas controlling plug 17 in its closed position, as shown in Figure 2. The upper end of the 90 lever 18 inclines forwardly across the top of the base and is provided with a soldering copper rest 23 at its upper end.

I have also provided a pilot light device 95 24, of ordinary construction, associated with the gas burner.

In practical use, the soldering copper rest 23 is normally held in the position shown in Figure 2 by the said spring 22, and the supply of gas to the burner is cut off. If it 100 is desired to start the burner, the operator places the soldering copper 12 in position within the furnace, as shown in Figure 1. This holds the gas controlling plug in open position, and permits the burner to be 105 ignited. So long as the soldering copper is in this position, the furnace will be heated, but at any time the soldering copper is re-

2
moved, the supply of gas is automatically shut off, thus avoiding the waste of gas that is ordinarily occasioned by operators removing the soldering copper and then failing to manually turn off the gas. The pilot light provides for automatically lighting the gas any time that it is turned on.

One of the advantages of my invention is that the gas controlling device is so shaped and constructed as to be readily and easily movable. Hence it will always be moved to open position when the weight of the handle of the soldering copper is placed on the receiver 23, and it will always be closed by the small spring 22 when the soldering copper is removed.

I claim as my invention:

In a tinsmith's furnace, the combination of a furnace body, a burner directed up-

wardly and inwardly into the body, said burner having at its outer end a smooth round opening, a gas supply pipe leading into the burner at one side of said round opening, a cut-off plug in said round opening capable in one position of closing the gas supply pipe and in another position of wholly or partially uncovering said gas supply pipe at its entrance into the burner, a screw adjustably mounted in the outer end of the plug, a lever fulcrumed to the frame and formed with a slot at one end designed to receive the screw and with a rest at the other end to receive a soldering copper, and a spring interposed between the lever and the body to normally hold the plug in its closed position.

Des Moines, Iowa, August 31, 1920.

TOM E. ROOKE.
